UNITED STATES PATENT OFFICE.

DAVID A. YARBROUGH, OF PETTEY, ALABAMA.

COTTON-CHOPPER.

SPECIFICATION forming part of Letters Patent No. 591,715, dated October 12, 1897.

Application filed July 3, 1897. Serial No. 643,373. (No model.)

To all whom it may concern:

Be it known that I, DAVID A. YARBROUGH, a citizen of the United States, residing at Pet-
tey, in the county of Limestone and State of
5 Alabama, have invented new and useful Im-
provements in Cotton-Choppers, of which the
following is a specification.

This invention relates to cotton-choppers,
and has for its object to provide a simple, effi-
10 cient, and easily-operated machine adapted
for "blocking out," "thinning," or "chop-
ping out" the young plants by drawing the
machine across a field at right angles to the
rows of plants.

15 The invention consists in features of con-
struction and novel combinations of parts in
a cotton-cultivating machine, as hereinafter
more particularly described and claimed.

In the annexed drawings, illustrating the
20 invention, Figure 1 is a vertical longitudinal
section of a cotton-chopping machine em-
bodying my invention. Fig. 2 is a plan of
the machine. Fig. 3 is a detail view of an
25 adjustable device for supporting the choppers
or hoes at any required elevation or so as to
work at any desired depth.

The machine comprises two runners, design-
20 nated by the reference-numeral 1, that may
be drawn readily over the cotton-bed, push-
30 ing aside clods and stones without much fric-
tion. These runners are connected by a front
cross-bar 2 and a rear cross-bar 3, which may
35 be of any suitable length, according to the
required width of the machine. The length
and breadth of the machine should be such
40 as will impart stability without making the
machine-frame unwieldy.

To the front cross-bar 2 are attached any
suitable draft devices 4, and a driver's seat 5
45 may be supported from this bar. In each
forward corner of the machine-frame there
may be arranged diagonal braces 6, secured
to the runners and front cross-bar, as shown.

On the tops of the runners are journal-
45 boxes 7 for the ends of a rock-shaft 8, that is
arranged transversely at about midway the
length of the machine-frame. To this rock-
shaft 8 are secured two plow-beams 9 at a
50 suitable distance apart. At their lower and
forwardly-curved ends these plow-beams 9
are connected by two parallel transversely-

arranged bars 10, which are set somewhat ob-
liquely to the ground by reason of the curva-
ture given to the rear ends of the plow-beams.
Between these two bars 10 is secured a series 55
of hoes or cotton-choppers 11, placed at con-
venient intervals apart and detachably se-
cured to the said bars by means of bolts 12
and nuts 13, which may also secure the bars
10 to the plow-beams. In the bars 10 and 60
hoe-blades 11 there are provided suitable
holes for passage of the bolts.

To the rock-shaft 8 there are secured a pair
of rearward and upward extended handles 14,
and to the hoe-carrying bars are secured 65
standards 15, the upper ends of which are
bolted to said handles. The handles 14 are
connected also with the plow-beams 9 by
means of braces 16, as shown.

To the central portion of the rear cross-bar 70
3 there is secured an upright 17, in which is
formed a vertically-elongated slot 18 to re-
ceive a bolt 19, that is passed through said
slot from one side of the upright 17 to the
other side for the purpose of attaching a ver- 75
tically-adjustable bracket 20, the upper end
of which is formed with a seat 21 to support
the cross-bar 22 of the handles 14, and thereby
hold the hoes or chopper-blades 11 at any re-
quired elevation according to the adjustment 80
given to the bracket 20, which adjustment
can be quickly changed by first loosening a
nut 23 on the bolt 19 that secures the said
bracket.

The upper part of the upright 17 is pro- 85
vided with a handle 24, by means of which
the rear end of the machine-frame can be
lifted in turning the machine at the end of a
field.

There is secured to the cross-bar 3 an up- 90
right 25, to which is fulerumed a lever 26,
that is extended forward at the right of the
driver. A rod 27 connects this lever 26 with
one of the beams 9, thus serving to support
the lever and permitting it to be used for lift- 95
ing the blades or choppers 11, so as to avoid
an obstruction, such as a stump.

By making the chopper-blades 11 detach-
able they can be removed for sharpening and
can be secured to their supporting-bars 10 at 100
any suitable intervals convenient for block-
ing out, as when the plants are to be only

partly thinned, or the choppers can be arranged closer together in chopping out to a "stand."

With a machine of suitable dimensions and construction as described from ten to twelve acres per day can be readily chopped out by the work of one man and a horse. A wider machine can be used with two draft-animals, so that an increased quantity of work can be 10 accomplished.

To avoid injury by frost and inclement weather, it is customary to at first thin out the plants only partially, which can be done with this machine after detaching some of 15 the hoes, so as to leave increased spaces between those remaining. The hoes can be subsequently arranged closer together for chopping out the plants to a stand. The machine can be operated with great efficiency 20 regardless of crooked rows or stony ground, as it slides along over the tops of the cotton-bed without much friction, always pushing clods and stones aside.

Any suitable draft devices may be attached 25 to the machine—that is to say, I may employ shafts or any means for attachment of a singletree or doubletree, according to circumstances.

By means of the vertically-adjustable 30 bracket 20 the hoes or chopper-blades 11 can be set lower or raised higher in the soil to suit varying conditions, or by the same means they can be supported entirely out of the ground when passing from one field to another.

Among other advantages presented by this cultivating-machine it may be said that it can be conveniently used for chopping out sorghum as well as cotton and other crops.

40 The location of the driver's seat and the absence of projecting mechanism that would obstruct his view enables him to readily avoid obstacles in the path of the machine, and by means of the adjacent hand-lever 26 45 he can readily raise the chopper-blades at any time or for any purpose without leaving his seat. The chopper-blades are so arranged that they will not become entangled with obstructions, and in case of breakage they can 50 be quickly and cheaply replaced.

What I claim as my invention is—

1. In a cotton-chopper, the combination of the runners, the front cross-bar and rear

cross-bar secured to said runners, a transversely-arranged rock-shaft journaled to the 55 runners at a point between the front and rear cross-bars, plow beams and handles secured to said rock-shaft, transversely-arranged bars secured to the downward and forwardly curved rear ends of said plow-beams, 60 chopper-blades detachably secured at intervals to and between said bars, standards connecting said bars with the plow-handles and braces connecting said handles with the plow-beams, and a vertically-adjustable bracket 65 supported on the rear cross-bar and having a seat for the cross-bar of the plow-handles to support the choppers at any required elevation, substantially as described.

2. In a cotton-chopper, the combination of 70 the runners, the front and rear cross-bars, the transversely-arranged rock-shaft, the plow-beams and the handles secured to said rock-shaft, the handle cross-bar, transversely-arranged bars secured to the downward and forwardly curved rear ends of the plow-beams, 75 the chopper-blades detachably secured to and between the said bars, an upright on the rear cross-bar, and a bracket vertically adjustable in a slot of said upright and provided 80 at the top with a seat for the cross-bar of the handles, to support the choppers at any required elevation, substantially as described.

3. In a cotton-chopper, the combination of 85 the runners connected by a front cross-bar and a rear cross-bar, the transversely-arranged rock-shaft, the plow beams and handles secured to said rock-shaft, transversely-arranged bars secured to the rear ends of the plow-beams, a series of chopper-blades 90 detachably secured to said bars, a vertically-adjustable bracket secured on the rear cross-bar and provided with a seat to support the plow-handles and hold the chopper-blades at any required elevation, a lever fulcrumed to 95 a standard on the rear cross-bar and extended to the driver's seat, and a rod connecting said lever with one of the plow-beams, substantially as described.

In testimony whereof I have hereunto set 100 my hand in presence of two subscribing witnesses.

DAVID A. YARBROUGH.
